BOBBIN WINDING MACHINE AND BOBBIN
SUPPLY MEANS THEREFORBurt A. Peterson, Rockford, Ill., assignor to
Barber-Colman Company, Rockford, Ill., a corporation of Illinois

Application July 19, 1947, Serial No. 762,146

26 Claims. (Cl. 242—32)

1

The invention pertains to bobbin winding machines of the type comprising a plurality of winding units disposed in laterally spaced relation and arranged for operation simultaneously in successive cycles to produce filling wound bobbins, and has more particular reference to the supply of empty bobbins to the respective winding units.

The primary object of the invention is to provide in combination with a multiple unit winding machine having a plurality of winding spindles arranged for simultaneous operation, a bobbin supply mechanism operative automatically in timed relation to the cyclic operation of the machine to insure at all times the supply to the respective units a group of bobbins of a number corresponding to the number of units so as to permit of the simultaneous movement of the empty bobbins into winding position.

Another object is to provide in an automatic multiple unit winding machine having an empty bobbin magazine common to the several units, a bobbin supply mechanism operative in timed relation to the successive winding cycles to deliver a predetermined number of bobbins to the magazine and to transport the same automatically to the several winding units for simultaneous movement into winding position.

Another object is to provide in combination with a multiple unit bobbin winding machine of the character set forth, means whereby empty bobbins are withdrawn from a supply hopper and delivered first to a magazine and then to a transport conveyor for presentation to the several winding units, together with means for correlating the delivery of bobbins to the magazine and the release thereof successively to the transport conveyor so as to insure the delivery to the conveyor at all times of a group of bobbins of the number corresponding to the number of winding units.

Still another object is to provide a bobbin supply mechanism for a winding machine including a transport conveyor, a magazine from which the bobbins are released one at a time to the conveyor and a supply conveyor for delivering bobbins to the magazine, together with means controlling the operation of the two conveyors so as to insure that in successive cycles of the winding machine a predetermined number of bobbins will be delivered to the machine.

A further object is to provide an empty bobbin supply mechanism including a hopper in which empty bobbins are placed in random relation, a conveyor, and means of an advantageous character for ensuring the effectual withdrawal of bobbins from the hopper by the conveyor.

Another object is to provide, in combination with a conveyor by which the bobbins are withdrawn from the hopper, ejector means oper-

2

ative to disengage from the conveyor and return to the hopper any bobbins which may be positioned improperly on the conveyor.

The objects of the invention thus generally stated, together with other and ancillary advantages, are attained by the construction and arrangement shown by way of illustration in the accompanying drawings, in which:

Fig. 1 is a fragmentary front elevational view of a multiple unit bobbin winding machine and its associated bobbin supply mechanism.

Fig. 2 is a sectional view taken approximately in the plane of line 2—2 of Fig. 1 and showing on an enlarged scale the construction of the supply conveyor.

Fig. 3 is a transverse sectional view on a somewhat larger scale taken approximately on the plane of line 3—3 of Fig. 1.

Fig. 4 is a fragmentary detail view partially in section showing a means for clamping the empty bobbins in their passage through the magazine.

Fig. 5 is a horizontal sectional view through the empty bobbin hopper and taken approximately in the plane of line 5—5 of Fig. 1.

Figs. 6 and 7 are fragmentary views illustrating the operation of ejecting bobbins improperly positioned on the supply conveyor.

Fig. 20 is a fragmentary side elevational view of the magazine and the associated feeler mechanism.

Fig. 21 is a fragmentary detail view showing the feeler mechanism in plan.

Fig. 22 is a fragmentary plan view of a portion of the mechanical control and showing particularly a clutch control mechanism for driving the transport conveyor.

Fig. 23 is a fragmentary front view of the parts shown in Fig. 22.

Fig. 24 is a schematic view and wiring diagram illustrating an electrical control mechanism for use in the embodiment shown in Figs. 13 to 15, inclusive.

Fig. 25 is a similar view with the control mechanism modified in accordance with the embodiment shown in Figs. 1 to 12, inclusive.

The invention concerns a bobbin winding machine of the type disclosed in Marcellus Patent No. 2,409,639, dated October 22, 1946, and comprising a series of winding units 14 disposed in laterally spaced relation and operative simultaneously in successive cycles under the control of a cycling mechanism 15 enclosed within a suitable housing at one end of the machine. More particularly my invention pertains to a winding machine of the above character modified as described in my copending application Serial No. 627,121, filed November 7, 1945, now abandoned, so as to include a transport conveyor 16 having a series of bobbin receptacles 17 thereon spaced apart according to the spacing of the winding units and adapted to receive empty bobbins b from a magazine common to the several units and positioned at one end of the conveyor. In Figs. 1 to 12 I have shown a magazine 18 in which the bobbins are arranged in a vertical stack, and in Figs. 13 to 15 a magazine 18' receiving and storing the bobbins in a spiral stack. Transfer devices 19 are provided for the several units and these devices are arranged for actuation simultaneously by means of a cam 20 forming part of the cycling mechanism 15, the arrangement being such that upon the movement of a group of bobbins into positions adjacent the respective winding units, the transfer devices 19 are actuated to carry the bobbins from their respective receptacles into winding position all as set forth in said copending application.

In accordance with the present invention, means is provided for supplying empty bobbins to the magazines 18 or 18' and releasing them one by one to the receptacles 17 of the transport conveyor 16 in proper timed relation to the cyclic operation of the winding machine, so that during one winding cycle a group of bobbins is withdrawn from the magazine and moved into position for transfer to the winding units preliminary to the succeeding cycle.

The bobbins are delivered to the magazine by means including a supply conveyor 21 associated with an empty bobbin hopper 22 and operative to withdraw bobbins one by one from the hopper and deliver the same to the magazine. As shown, the supply conveyor is in the form of an inclined elevator operative to discharge the bobbins onto a runway or slide 23 by which they are carried to the upper end of the magazine 18.

Operation of the two conveyors in proper timed relation to each other and to the winding machine is governed by a control mechanism which may be mechanical in character as shown in Figs. 16 to 20, or electrical as shown in Figs. 24 and 25. To avoid possible injury to the bobbin supply mechanism, due to improperly positioned bobbins on the supply conveyor 21, the latter has associated therewith an ejector 24, the function of which is to dislodge from the conveyor any bobbins improperly positioned thereon and to return such bobbins to the hopper 22.

The bobbins b are regularly equipped with a plurality of steel rings c encircling the butt ends. Preferably, these rings are utilized in supporting and guiding the bobbins into and through the magazine. In the embodiment of my invention shown in Figs. 1 to 12, inclusive, the magazine 18 stores the bobbins in a vertical stack with the bobbins horizontally disposed. It comprises a pair of vertically disposed bars 25 spaced apart laterally a distance corresponding to the diameter of the butt ends of the bobbins but less than that of the rings c, and a second pair of bars 26 also spaced apart but in this instance according to the diameter of the bobbins adjacent their tip ends. These bars are disposed forwardly of an upright frame 27 and suitably secured to the latter. At their lower ends (Figs. 1 and 3) the bars 25 and 26 are disposed above one end of the transport conveyor 16 and in spaced relation thereto so as to permit of travel beneath the bars of the bobbin receptacles 17 on the conveyor. At their upper ends the bars 25 curve forwardly and somewhat upwardly for connection with spaced side rails 28 inclined downwardly and rearwardly, the spacing of the side rails 28 like that of the bars 25 corresponding to the diameter of the butt ends of the bobbins so that the bobbin rings c engage with the upper surfaces of the rails and thus support the bobbins for movement along the rails. At their upper forward ends the rails 28 curve laterally as shown at 29 (Figs. 3 and 11) and connect with a pair of bars 30 spaced apart according to the spacing of the rails 28 and constituting the inclined slideway 23.

Referring now to Figs. 1 and 2, the supply conveyor 21 by which the empty bobbins are delivered to the slideway 23 comprises an upwardly and laterally inclined frame supported by uprights 31 on a base frame 31a. The conveyor frame consists of a pair of angle bars 32 and cross plates 32a supporting a slide plate 33 slotted for the passage of a series of bobbin seizing devices or hooks 34 mounted at spaced intervals on an endless conveyor chain 35 running over sprockets 36 and 36a mounted respectively at the upper and lower ends of the frame. The upper sprocket is driven by a motor 37 through a speed reducer 37b having a belt and pulley connection 37c with the sprocket shaft 36b.

The bobbin seizing devices 34 are herein shown (Fig. 2) in the form of U-shaped clips composed of two strips of sheet metal having portions 38 forming the links of the chain, the two strips being brought together at one side of the chain

to form a shank 39 traveling in a slot 40 in the slide plate 33.

The hopper 22 (Figs. 1 and 5) associated with the lower portion of the supply conveyor is open at its upper end for the introduction of the empty bobbins and is provided with an upwardly and laterally inclined slot 41 for the passage of the chain hooks or clips 34. Inasmuch as the bobbins when thus introduced are disposed in random relation, the hopper is shaped so as to cause the bobbins to gravitate toward the slot 41. Thus it comprises two opposed V-shaped or trough-like lower portions 42 and 43 converging at the bottom of the hopper and having sides 42a and 43a merging with the vertical side walls 44. The slot 41 for the passage of the clips 34 on the chain 35 is formed in the bottom of the trough portion 43 which is inclined to conform to the inclination of the conveyor 21 and its frame 32.

To facilitate seizure of bobbins by the clips 34, means is provided at the bottom of the hopper which, in general, serves to agitate the bobbins and to position them in alignment with the conveyor. This means comprises a pair of segmental plates 45 mounted upon a shaft 46 (Fig. 9) journaled in a bracket 47. On a parallel shaft 48 are mounted a pair of cams 49 operating upon rollers 50 carried by the respective plates 45, the rollers being urged toward the cams by means of springs 51. The bracket 47 is mounted adjacent the wall of the hopper, and the blades are arranged for operation through spaced slots 52 in the bottom of the trough portion 42, the length of stroke of each plate being such that in its lowermost position the plate is withdrawn to a position substantially flush with the walls of the trough. The two plates 45 are spaced apart a distance somewhat greater than the diameter of the butt ends of the bobbins, and they are raised and lowered in succession in the rotation of the shaft 46. The latter may be driven in any suitable way. As shown, it has a belt and pulley connection 53 with the lower sprocket 36a of the conveyor.

It will be observed from Fig. 5 that the plates 45 serve to form a narrow channel in the bottom of the hopper, the plates forming movable side walls alternately withdrawn from the hopper so as to open the same laterally and permit movement of the bobbins into the channel. The bottom of the channel is formed by the bottom of the trough portion 42 of the hopper and, being inclined downwardly and laterally, bobbins received into the channel slide downwardly for engagement by the clips 34 moving upwardly along the slot 41 in the bottom of the trough portion 43. Since the side portions of the clips 34 are spaced apart a distance corresponding to the diameter of the butt ends of the bobbins, but less than the rings c thereof, the latter are engaged by the clips so that the bobbins are withdrawn upwardly by the conveyor.

It has been found in practice that in the withdrawal of bobbins properly positioned within the clips, other bobbins not properly positioned are also apt to be withdrawn. In this connection, reference is made to Figs. 6 and 7 of the drawings showing bobbins arranged in various positions on the conveyor. To remove such improperly positioned bobbins and to return them to the hopper is the function of the ejector 24. This device comprises a rotary brush 54 mounted on a swinging frame 55 (Fig. 8) pivoted at 56, the free end of the frame and therefore the brush 54

being held by the action of gravity in yieldable relation to the conveyor. To assist the action of gravity, a spring 57 may be employed. Movement of the brush 54 toward the conveyor is limited by a stop 58 adjustable so as to position the brush in variably spaced relation to the slide plate 33, the preferred spacing being somewhat less than the diameter of the butt end of the bobbin. It will be seen that in the event a bobbin is not properly positioned on the conveyor, e. g., with the rings c engaging the side portions of the clip as in Fig. 6, or resting upon another bobbin as in Fig. 7, the bobbin will be supported in spaced relation to the slide plate 33 and when thus supported will be engaged by the brush 54 and ejected from the conveyor.

The brush 54 may be driven in any suitable way. As shown (Fig. 1), it is driven by the conveyor drive motor 37 through the speed reducer 37b, the latter having a belt and pulley connection 61 with an idler 62 coaxial with the pivot 56 of the frame. The idler in turn has a belt and pulley connection 63 with the brush. In practice, the brush 54 is rotated rapidly so that the improperly positioned bobbins are ejected with considerable force. For this reason, the hopper 22 is constructed to provide an upward extension 64 (Fig. 1) open at the side adjacent the brush and having a back stop 65 in opposed spaced relation to the brush which is struck by the ejected bobbins, the latter falling into the hopper. To assist in retaining the bobbins properly on the conveyor after passage beneath the brush, the frame 55 is preferably equipped with a yieldable pressure member in the form of a pivoted flap 66 (Fig. 8).

When the bobbins reach the top of the supply conveyor 21, they are discharged onto the inclined slideway 23. In view of the spacing of the bars 30 thereof, the tip ends of the bobbins fall by gravity through the slot formed between the bars and the bobbins move by gravity along the slideway 23 and thence onto the rails 28 (Figs. 3 and 10) whence they move into the magazine over the upper curved portions 25a thereof. To dampen the swinging motion of the bobbins as the tip ends thereof fall by gravity through the slots formed between the bars 30 of the slide 23, the latter is preferably equipped with a flap 67 pivoted on the bracket 68 in overlying relation to the slideway and yieldably engageable with the butt ends of the bobbins.

Empty bobbins pass into and through the magazine under the control of an escapement mechanism. Movement of bobbins into the magazine is controlled by a pair of escapement fingers 69, 70, release of bobbins from the magazine is under the control of a pair of escapement fingers 71, 72, while movement downwardly in the magazine is governed by a series of fingers 73. The fingers 69, 70 and 73 are mounted on a vertical rockshaft 77, and the two lower fingers 71, 72 are mounted on a rockshaft 77a alined with the shaft 77.

The rockshaft 77 is driven by the supply conveyor by means of a shaft 78 (Figs. 3 and 25) having a gearing connection 78a with the upper sprocket shaft 36b of the conveyor, and a crank and pitman connection 79 with the rockshaft. The lower rockshaft 77a has a crank and pitman connection 80 with idler sprocket shaft 81 of the transport conveyor.

Referring now to Figs. 3, 10 and 11, the uppermost escapement fingers 69 and 70 are made of a length somewhat greater than the other

escapement fingers so as to extend into operative association with the bobbin supported on the rails 28; and the uppermost finger 69 is made somewhat longer than the adjacent finger 70. Both fingers have bent end portions 81 and 82 movable through slots 83 in the rails 28. As seen in Fig. 10, the bent portions 81, 82 are in this instance spaced apart a distance sufficient to allow passage of two bobbins at a time into the magazine.

The lower escapement fingers 71, 72 are spaced apart vertically a distance corresponding to the diameter of the butt ends of the bobbins so as to permit the release of bobbins from the magazine one at a time. The intermediate fingers 73 on the other hand may be spaced apart a substantially greater distance (a suitable multiple of the bobbin head diameter). In order to control the descent of the bobbins through the magazine and to maintain them in a substantially horizontal position, each of the lower and intermediate fingers have bent end portions 74 (Fig. 11) for engagement by the tip ends of the bobbins, and arms 75 for engagement by the butt ends.

Upon entering the magazine, the bobbins shift their positions from a substantially vertical or upright position into a horizontal position. Thus, as the bobbins escape past the upper set of fingers 69, 70 they pass onto the curved portions 25a of the bars 25 and then into the vertical portions of the ways formed between the bars. In this latter movement, the bobbins assume a horizontal position due to the fact that the tip portions of the bobbins first engage with the bent ends 74 of the uppermost fingers 73, while the head ends continue to fall until they rest upon the arms 75 rearwardly of said bent ends. To prevent the bobbins from moving rearwardly while passing over the curved portions 25a of the tracks 25, the magazine is provided with a curved guide 84 for engagement by the head ends of the bobbins.

Owing to the fact that the bobbins enter the magazine at random without regard to the operation of the upper fingers 69, 70, the latter are mounted so as to be capable of yielding relative to the rockshaft. For this purpose, each finger has a yieldable driving connection with the rockshaft 71 comprising a collar 86 fast on the rockshaft and carrying a pin 87 connected by a contractile spring 88 with a pin 87a on the escapement finger. The pin 87 projects through a slot 83a in the finger, and the arrangement is such that when the finger is blocked by engagement with a bobbin, the shaft is permitted to rock without turning the fingers, the spring yielding to permit the pin 87 to turn in its slot.

To facilitate entry of the lower escapement fingers 71, 72 and the intermediate escapement fingers 73 between adjacent bobbins in the magazine, means is provided for clamping such bobbins in horizontal positions just before the fingers enter their positions between the bobbins. For this purpose, I employ a cam actuated clamping member 89 (Figs. 3, 4 and 11). In the present instance, the clamping member is generally U-shaped in form (Fig. 4) and is mounted to slide between spaced parallel guides 90 forming part of the magazine frame 27. At vertically spaced points, the clamping member carries a plurality of cam blocks 91 (Fig. 4) each engageable by a roller follower 92 on an arm 92a fast on the rockshaft 71. A contractile spring 93 holds each cam block against its roller follower and the arrangement is such that when the shaft 71 is rocked in either direction to carry

a set of fingers into active positions, the roller followers engage their respective cam blocks to force the clamping member 89 against the butt ends of the bobbins, forcing the bobbin rings c against the bars 25 (Fig. 4). As shown at 89a in Fig. 3, the upper end of the clamping member 89 is preferably rounded to guide the dropping bobbins so as to position their butt ends forwardly of the clamping members and against the bars 25.

In Figs. 13 to 15, I have shown the modified form of magazine 18'. In this instance, the magazine is constructed so that the bobbins move in a spiral path 95 from the top to bottom of the magazine and are frictionally supported in vertical position so as to retard the descent of the bobbins through the magazine. Owing to the spiral arrangement of the bobbins, the capacity of the magazine is substantially increased.

The magazine is generally cylindrical in form and, as shown in Fig. 15, it is composed of two concentric cylinders 96, 96a spaced apart a distance corresponding to the diameter of the bobbin butts but less than that of the bobbin rings c. The outer cylinder 96 is formed with a spiral slot 97 the upper end of which opens tangentially of the cylinder in alignment with a guide 97a on the slide 23, the guide being attached to the upper end of the magazine by a bracket 96b. The inner cylinder 96a is formed with a spiral groove 98 in opposed relation to the slot 97 so that the lower edges of the slot and groove are adapted to be engaged by the bobbin rings c (Fig. 15) to support the bobbins in their passage downwardly between the cylinders. It will be observed that the bobbins enter the magazine in an upright position and are disposed vertically during their downward passage. To permit of entry in this position, the outer cylinder is cut away at the upper end of the slot to form a passage 98c (Fig. 13).

The lower end of the slot 97 similarly opens tangentially of the cylinder 96 and merges into a curved slideway 99 such that before escaping from the magazine the bobbins may shift gradually from vertical to generally horizontal positions. In opposed relation to the slideway 99 is a guide 100, the spacing between the members being such as to accommodate the butt ends of the bobbins.

The specific construction of the magazine will be evident from Fig. 15. In addition to the cylinders 96 and 96a it comprises a top plate 101 and a bottom plate 102 with spacers 103 between the two cylinders located in suitably spaced vertical relation. At one side of the magazine the two cylinders have downwardly projecting portions 103a and 103b containing the lower end portion of the guideway 97.

The magazine is supported by means of a bracket 104 attached to the frame 27 and also by a bracket 105 spaced below the bracket 104. A tie rod 106 extends upwardly from the bracket 105 through the bracket 104 and bottom plate 102 and is connected at its upper end to the top plate 101 of the magazine. A spacer sleeve 107 is interposed between the bracket 105 and the bottom plate 102 of the magazine and the tie rod is provided with a nut 108 to clamp the parts together.

In the embodiment of the invention, the bobbins are permitted to enter the magazine freely from the slideway 23. As they enter upon the bottom slideway 99 (Fig. 14) they engage a pair of escapement fingers 109 and 110 mounted on a

rockshaft 111 (Figs. 14 and 16) and arranged for actuation by a crank and pitman connection 111a with the transport conveyor 16. Since the bobbins move along the slide 99 at random, the fingers 109, 110 are yieldably connected with the rockshaft in the same way as the fingers 69, 70 (Fig. 11).

The fingers 109, 110 have their end portions spaced apart a distance corresponding to the diameter of the butt ends of the bobbins so as to release one bobbin at a time. In order to position the bobbins in perpendicular relation to the slide-way at the point of entry of the escapement fingers between adjacent bobbins, the lower finger 110 is preferably constructed in two parts 112 and 113 rigidly secured together but spaced apart as shown clearly in Fig. 14 so that the portion 112 engages the butt end of the bobbin 113 and the tip end thereof.

Upon their release by the escapement fingers 109, 113, the bobbins move to the bottom of the slideway 99 where they are released from the magazine by a pair of escapement fingers 114, 115. These fingers are constructed like the fingers 71, 72 in the previous modification and serve to release the bobbins one at a time to the bobbin receptacles 17.

As set forth in my said copending application, the transport conveyor 16 is operatively associated with the winding machine and, in addition to performing the function of carrying empty bobbins into position for transfer to their respective winding units, may serve additionally to carry wound bobbins doffed from the machine at the end of the preceding cycle to a predetermined delivery point. The operation of the transport conveyor is therefore correlated with the operation of the winding machine.

Referring now to Figs. 16 and 18 of the drawings, the transport conveyor comprises two endless sprocket chains 115 running over sprockets on a drive shaft 116, and an idler shaft 117. The two chains are disposed in laterally spaced relation and equipped with the bobbin receptacles 17 and also with a second series of bobbin pockets 118 (Fig. 19), the latter alternating with the receptacles 17. The shafts 116 and 117 are suitably journaled in the frame of the winding machine so that the conveyor is supported with the upper run thereof below a series of winding units 119. Each of said units includes a winding spindle 120 with a chuck 121 for gripping the butt end of the bobbin, a centering slide 122 with a tip 122a for engagement with the tip end of the bobbin and a yarn traversing cam 123 (shown schematically in Fig. 24) encircling the spindle and mounted in a slide 123a for movement axially of the bobbin as it is wound. For a complete disclosure of the construction of the winding units, reference is made to Marcellus Patent No. 2,409,639.

Upon the completion of one winding cycle, wound bobbins are doffed from each of the winding units by withdrawal of their respective centering slides 122, the bobbins dropping into underlying pockets 118 on the conveyor. Thereupon, empty bobbins are transferred from the receptacles 17 to the winding units, preparatory to the next winding cycle. This is accomplished in the manner disclosed in my said copending application, by means of the transfer devices 19, there being one for each winding unit. The transfer devices comprise transfer arms 124 mounted upon parallel rockshafts 125 carrying lever arms 126 and actuated simultaneously by a

bar 127 operatively associated with the cam 20 forming part of the cycling mechanism 15 of the winding machine.

As seen in Fig. 16, each of the bobbin receptacles 17 is made in two aligned sections respectively supported on the chains 115 and arranged to support the empty bobbins with the butt ends thereof resting in the sections 17a and the tip ends in the section 17b. The two sections are thus spaced apart so that the intermediate portion of each bobbin may be engaged by a pair of notched fingers 129 mounted on the free ends of the arm 124.

In accordance with the present invention, the supply conveyor is controlled in its operation so that it is advanced in timed relation to the winding machine cycle and stopped when the supply of empty bobbins in the magazine is sufficient to meet the requirements of the machine in the next winding cycle. For this purpose, I provide a control mechanism which, as first above indicated, may be either electrical or mechanical in character. In either case, the supply conveyor is initiated in operation at the same time as or substantially concurrently with the movement of the bobbins out of the magazine in the operation of the transport conveyor, and is stopped when a predetermined number of bobbins has been received in the magazine as determined by the operation of a feeler associated with the upper portion of the magazine and responsive to the number of bobbins received in the magazine either by detecting the accumulation of a predetermined number of bobbins in the magazine or the number of bobbins delivered thereto.

The control mechanism shown in Figs. 16 to 23 is entirely mechanical except for the use of electric drive motors. The transport conveyor is driven by an electric motor 130 through the medium of a speed reducer 131 having a belt and pulley connection 132 with the motor. The sprocket drive shaft 116 constitutes the output shaft of the speed reducer and the operation of this shaft is under the control of a clutch 133 operatively associated with one of the rockshafts 125.

The clutch 133 is engaged to start the transport conveyor 16 at or near the beginning of each winding cycle of the machine so that during such cycle, the bobbins wound in the preceding cycle are advanced to their predetermined point of delivery and a group of empty bobbins carried into position for transfer to the winding units. Engagement of the clutch is accomplished in the present instance through the medium of a lever means 134, a slide 135 having a disengageable connection with the lever means and an arm 136 fast on one of the rockshafts 125. The lever means comprises a clutch shifting arm 137 fulcrumed intermediate its ends and pivoted to a second lever 138 similarly fulcrumed. A coiled contractile spring 139 tends to swing these levers in a direction to disengage the clutch. The slide 135 is suitably supported in a frame member 135a and it carries an adjustable abutment in the form of a screw 140 for engagement with a roller 141 on the arm 136. To the opposite end of the slide is pivoted a latch member 142, and when this member occupies a position in blocking relation to the lever 138, movement of the slide by the arm 136 will effect engagement of the clutch 133. This occurs at or just prior to the beginning of each winding cycle as an incident to the return of the transfer arms 124 by the cam 20 of the machine cycling mechanism. A spring 142a

tends to swing latch member 142 downwardly (Fig. 19) and to hold a stop pin 142b on the slide against the frame member 135a.

In the relationship of the parts shown in Fig. 16, the latch 142 occupies a blocking position relative to the free end of the lever 138 and serves to hold the clutch engaged and the conveyor in motion. The latch is disengaged from the lever to stop the conveyor by an output counter 143 driven by the conveyor. The clutch disengaging means, as herein shown, comprises a pivoted dog 144 carrying at one end a screw 145 underlying the latch 142 and having its other end arranged for actuation by the counter 143. The latter comprises a driven gear 146 and a single toothed driving gear 147 fast on the sprocket drive shaft 116, a stepping movement being imparted to the gear 146 with each revolution of the sprocket shaft. On the gear 146 is a lug 148 engageable with the dog 144 to trip the latter upon the movement of a predetermined number of empty bobbins into positions adjacent their respective winding units. As will be clear from Fig. 16, the lug 148 on gear 146 actuates the dog 144 to lift latch 142 (Fig. 19) and thereby release the lever 138 to the action of the spring 139 so as to effect disengagement of the clutch.

Reengagement of the latch 142 with the lever 138 preparatory to the next advance of the conveyor, occurs upon the completion of a winding cycle of the machine, when the transfer arms 124 are actuated by the cam 20 to carry empty bobbins from the receptacle 17 to the winding units. In this operation, the arm 136 is swung in a direction to permit movement of the slide 135 by the spring 142a. After a limited movement of the slide, latch member 142 is permitted to drop into blocking relation to the lever 138.

It will thus be seen that with the drive motor 130 operating continuously, the clutch 133 is engaged to advance the conveyor during one winding cycle so as to present a group of empty bobbins to their respective winding units and to carry the corresponding group of doffed wound bobbins to the predetermined point of delivery. The extent of movement is determined by the gear output counter 143 and its lug so that after the advance of the conveyor the required distance, the dog 144 is actuated to disengage latch 142 and thereby effect disengagement of the clutch 133. Upon the completion of the cycle, the transfer arms 124 are swung upwardly and in this operation, the latch 142 is reengaged with the lever 138 preparatory to the next advance of the conveyor during the succeeding cycle. It will of course be understood that in each advancing movement of the transport conveyor, empty bobbins are delivered to the receptacles 17 by the operation of the escapement fingers 114, 115, the latter being actuated by the rockshaft 111 driven from the sprocket shaft 117 through the crank and pitman connection 111a.

In this embodiment of the invention, the supply conveyor 21 is actuated by its motor 37 through the medium of the speed reducer 37b and an interposed clutch 149, in an arrangement such that the conveyor is started automatically upon the release of empty bobbins to the receptacles 17 in the operation of the transport conveyor, and is stopped when a predetermined number of bobbins has accumulated in the magazine. The clutch has a shifting lever 150 (Fig. 75

16) normally held in engaged position against the action of a spring 151 by a latch 152 controlled by a feeler device 153 responsive to the presence of a predetermined number of bobbins 5 in the magazine. For a purpose which will presently appear, the latch 152 is yieldably mounted (Fig. 17) on a bar 152a pivotally connected with the shifting lever 150.

The feeler device is arranged for periodic actuation toward and from the spiral path through which the empty bobbins pass in their descent through the magazine, the device being herein shown as associated with the upper portion of that path. The feeler device comprises a rod 153a having a feeler shoe 154 at one end thereof and its other end mounted on a floating lever 155 pivoted at 156 on an arm 157 carried by a constantly oscillating rockshaft 158. A spring 159 tends to hold the lever against a stop 160, but when the feeler shoe 154 is blocked so as to be incapable of entering the spiral slot 97, the upper end of the lever moves away from its stop 160 against the action of the spring 159. Thus it moves out of blocking relation to the latch 152, releasing the latch and thereby the clutch member 150 to the spring 151, to cause disengagement of the clutch. The shaft 158 is oscillated in the present instance by means of a cam 161 on the sprocket shaft 36b of the supply conveyor 21. The cam operates upon a lever 163 fulcrumed intermediate its ends and connected by a link 164 with an arm 165 on the rockshaft 158.

In view of the fact that the bobbins move 35 through the magazine in random relation, the feeler device is constructed so as not to be responsive to the presence of a single bobbin in the path of the shoe 154. For this purpose, the shoe is made of substantial width (Fig. 21) and 40 is pivoted at its center upon the rod 153a, the arrangement being such that each end of the shoe must engage with a bobbin before the feeler device is effectually blocked, the position occupied by the shoe when it engages with only one bobbin being shown in broken lines in Fig. 21. A pair of stop pins 166 (Fig. 21) respectively engage with opposite ends of the shoe when the latter moves in a direction away from the magazine so as to restore the shoe to an intermediate position with its forward surface 45 concentric with the periphery of the magazine.

Reengagement of the clutch 149 is accomplished under the control of the transport conveyor so that after the delivery of a few empty bobbins to the latter conveyor as an incident to 55 a short advance thereof, the supply conveyor is again actuated to replenish the supply of bobbins in the magazine. For this purpose, an arm 167 is mounted on the upper end of a vertical rockshaft 168 suitably supported in the machine frame. The arm is engageable with a lug 169 (Fig. 17) on the latch supporting bar 152a. At its lower end the shaft carries an arm 170 with a roller follower 171 engaged by a cam disk 172 driven by a speed reducer 173 connected with the idler sprocket shaft 117 of the conveyor. The arrangement is such that at a predetermined time interval after the start of the transport conveyor and the ensuing release of bobbins from the magazine, the rockshaft 168 is actuated to 60 reengage the clutch 149 and to reset the latch 152 with respect to the floating lever 155. Because of the movement of bobbins in spaced relation along their spiral path, the feeler is no longer blocked and therefore occupies the posi-

tion shown in Figs. 16 and 17. Accordingly, movement of the latch bar 152a by the rockshaft 168 causes the latch to ride over the floating lever and into holding engagement therewith. The operation of the supply conveyor is thus resumed, pending interruption when the feeler 153 again detects a filled condition of the magazine.

Summarizing the operation of the mechanical control mechanism, the transport conveyor is initiated in operation by the cycling mechanism 15 of the winding machine acting through the medium of the transfer devices 19. This occurs near the end of the machine cycling operation just in advance of the initiation of a new winding cycle. Thus, in the return movement of the transfer arms 124 (Fig. 16) the arm 136 on one of the rockshafts 125 actuates the slide 135 so as to shift the lever means 134 against the action of spring 139 and cause engagement of the clutch 133. When the transport conveyor has been operated to advance the predetermined number of bobbins into positions adjacent the respective winding units, lug 143 on gear 146 trips dog 144 to disengage latch 142 from the lever 138, releasing the lever means to the action of spring 139 and disengaging the clutch. Latch 142 is reengaged with lever 138 as an incident to the operation of the transfer devices 19 during the succeeding operation of the cycling mechanism 15.

In the advance of the transport conveyor, empty bobbins are delivered one-by-one to the receptacles 17 in the operation of the escapement fingers 114, 115 which are oscillated in timed relation to the conveyor. Release of bobbins from the lower end of the magazine results in a downward movement of the bobbins in the upper portion of the magazine out of the path of the feeler 153 so that floating lever 155 again assumes its active position. Accordingly, in the next operation of rockshaft 168, bar 152a and lever 150 are actuated to engage clutch 149, and the latter is held engaged by latch 152 coacting with the floating lever 155. Operation of the conveyor continues until the number of bobbins accumulating in the magazine is sufficient to block the feeler 153 and cause the floating lever 155 to move out of engagement with the latch 152, thereby releasing the clutch shifting bar 152a to the action of spring 151 to disengage the clutch. It will be understood that the term "magazine" as herein used is intended to include any suitable structure for accumulating the supply of empty bobbins under the control of the feeler.

In Figs. 24 and 25, I have shown two electrical control mechanisms respectively adapted for use with the two types of empty bobbin magazines shown in the embodiments of Figs. 1 to 12 and 13 to 15, and performing in general the same functions as the mechanical control above described.

Referring first to Fig. 24, the driving motors 37 and 130 for the supply and transport conveyors 16 and 21 respectively are controlled by an electromagnetic relay generally designated 175 in conjunction with a switch 176 operated by the winding machine during each winding cycle and two control switches 177 and 178. The first of these control switches is responsive to the delivery by the transport conveyor of a predetermined number of empty bobbins into positions adjacent the respective winding units 14 and the other is responsive to the delivery of a corresponding number of bobbins to the magazine.

The relay 175 comprises an armature in the form of an elongated bar 180 having an actuating coil 181 and a pair of disks 182 and 183 forming the movable contact elements of two switches 184 and 185. Upon energization of the coil 181, the armature bar moves in a direction to close the switches 184 and 185 (to the right in Fig. 4) against the action of a coiled spring 186 tending to hold the bar against a stop 186a. The armature bar is adapted to be held in switch closing position by two latch devices 187 and 188, comprising lugs 189 and 190 formed on the bar, and latch elements 191 and 192 having stems 193 and 194 constituting armatures for two coils 195 and 196. In general, the arrangement is such that the armature bar 180 is moved in a switch closing position upon energization of the coil 181, is held in such position against the action of the spring 186 by the latch devices 187 and 188, and is released for movement in a switch opening direction by the energization of the coils 195 and 196, the former controlled by switch 177 responsive to the movement of the transport conveyor in delivering a predetermined number of empty bobbins to the winding units, and the latter controlled by switch 178 responsive to the passage into the magazine of a corresponding number of bobbins.

In the instant embodiment of the invention, the transport and supply conveyors are started in operation by the winding machine immediately following initiation of a winding cycle by the cycling mechanism 15, through closure of the switch 176 controlling energization of the relay coil 181. As shown, this switch comprises a movable contact element 197 fast on a stem 198 carrying a cam block 199 and yieldably supported in a stationary part of the winding machine frame. The switch is closed in the initial portion of the advancing movement of the traverse slide 123a, by a cam block 200 mounted on a lever 201 pivoted to the traverse slide 123a, the lever being held against a stop 202 by a spring 203 so as to be yieldable in the return of the slide to its initial retracted position at the conclusion of the winding cycle.

The switch 177 controlling energization of relay latch coil 195 is arranged for actuation by a cam 204 forming part of an output counter 205. The latter is driven by the transport conveyor and is so timed with respect to the operation of the conveyor that the cam 204 makes one complete revolution for each advance of the conveyor a distance sufficient to deliver the predetermined number of bobbins to the respective winding units. As shown, the cam 204 is fast on an output shaft 206 of the counter, and the counter is actuated by a lateral extension 207 of the idler sprocket shaft 117 of the transport conveyor.

The switch 178 controlling energization of relay latch coil 196 is similarly arranged for actuation by a cam 208 on the output shaft 209 of an input counter 210 responsive to the delivery of empty bobbins to the magazine 18' under the control of a feeler 211. In the present instance, the output shaft 209 of the counter is driven by a pawl and ratchet device 212 actuated electromagnetically in response to the operation of the feeler 211. The pawl and ratchet device 212 comprises a ratchet wheel 213 operated by a pawl 214 pivoted on a lever 215. The latter carries a rod 216 forming the armature of a coil 217 which when energized advances the lever 215 against the action of a spring 218. The coil 217 is controlled by a switch 219 having a stationary con-

tact 220 and a movable contact 221. This movable contact is mounted on an arm 222 arranged for actuation by the feeler 211 so as to close the switch 219 each time an empty bobbin passes the feeler in the movement of the bobbin downwardly in the upper portion of the magazine. As shown, the feeler is mounted on a spring finger 223 so as to project into the spiral passage 95 of the magazine.

Assuming that the transport and supply conveyors are in stopped position and that the bobbin winding machine is in condition for the initiation of a new winding cycle, the machine is started by the closure of a starting switch 224 interposed in a supply line 225, the other side 226 of the line being provided with an emergency stop switch 227. Upon closure of the switch 224, a circuit is completed to a motor 228 constituting the main drive motor for the winding machine and also to a motor 229 forming a part of the cycling mechanism 15 of the machine. Upon the ensuing advance of the traverse slide of the winding machine, the switch 176 is closed to establish a circuit from supply line 225 through a conductor 230, switch 176, conductor 231, relay coil 181 and conductor 232 to the opposite supply line 226. As a result, armature bar 180 is shifted to the right against the action of spring 186 closing switches 184 and 185. Switch 184 completes a circuit to motor 37 of the supply conveyor through conductors 232a and 232b, and switch 185 completes a circuit to transport conveyor motor 130 through conductors 232b, 232c and 232d.

At the time of the initial closure of starting switch 224, latch coils 195 and 196 are both energized so as to retract latch members 191 and 192 from engagement with the armature bar 180. Latch coil 195 is connected in a circuit including a conductor 233 connected with supply line 225, counter switch 177 closed while the transport conveyor is in stopped position, a conductor 234, latch coil 195, and conductors 236 and 232, the latter connected with the supply line 226. The circuit for latch coil 196 includes a conductor 237 connected with supply line 225, latch coil 196, a conductor 238, input counter switch 178, and a conductor 239 leading to supply line 226, switch 178 being closed because in the assumed condition the predetermined maximum number of bobbins has previously been delivered to the magazine.

In the operation of the supply conveyor following closure of relay switch 184, cam 208 operates in response to the delivery of bobbins to the magazine, opening switch 178 and thereby de-energizing latch coil 196. Similarly, the operation of the transport conveyor causes cam 204 to open switch 177, thereby deenergizing latch coil 195. The arrangement is such, however, that armature coil 181 is maintained energized by switch 176 until after the opening of switch 177 so that the armature bar is held by coil 181 in its shifted position against the action of spring 186 so as to allow time for the deenergization of latch coil 195 by the opening of switch 177. De-energization of coils 195 and 196 causes latch members 191 and 192 to move into holding engagement with lugs 189 and 190 of the armature bar, retaining the latter in its shifted position with switches 184 and 185 controlling the supply and transport motors closed.

The transport conveyor continues its advancing movement until the predetermined number of empty bobbins has been released from the magazine into the bobbin receptacles 17 and delivered

by the conveyor into positions adjacent the respective winding units. When this occurs, cam 204 of the output counter closes switch 177 and causes energization of latch coil 195, thereby disengaging latch element 191 from lug 189 so as to release armature bar 180 to the action of the spring 186. Switch 185 is therefore opened to stop the transport conveyor motor 130.

Interruption of the supply conveyor will occur simultaneously with the interruption of the operation of the transport conveyor, subject, however, to the delivery to the magazine of an adequate supply of empty bobbins as determined by the input counter 210. Thus, if at the time of stoppage of the transport conveyor the predetermined number of empty bobbins has not been delivered to the magazine by the supply conveyor, latch element 192 will remain in blocking relation to lug 190 of armature bar 180 and prevent opening of switch 184 controlling the supply conveyor motor 37. In this connection, the disks 182 and 183 forming the movable contacts of the switches 184 and 185 are differentially spaced with respect to their stationary contacts so that in the movement of the armature bar upon release by the latch device 187 sufficient to open switch 185 to the transport conveyor, the switch 184 will be held closed by the latch device 188, and this switch 184 will be allowed to open only upon the retraction of the latch element 192 by the energization of latch coil 196 under the control of input counter switch 178. Accordingly, if at the time of stoppage of the transport conveyor an adequate supply of empty bobbins has not been delivered to the magazine, latch device 188 will remain effective to prevent opening of the switch 184 until the input counter 210 responding to the feeler 211 closes switch 178 and disengages latch device 188.

To permit of the operation of switches 184 and 185 in the manner above described, the disks 182 and 183 are yieldably held by springs 240 against stop collars 241 and 242 adjustably secured to the bar, the collar 242 being so adjusted as to engage disk 183 to open the switch 185 before collar 241 engages disk 182 to open switch 184.

Summarizing the operation of this control mechanism, it will be seen that a winding cycle of the bobbin winding machine is initiated by the closure of starting switch 224, and that in the initial advance of the traverse slide 123a of the machine, switch 176 is closed and relay coil 181 energized to close switches 184 and 185 to start both of the conveyors simultaneously. Accordingly, during the winding cycle thus initiated, empty bobbins are released from the magazine and delivered into positions adjacent the respective winding units of the machine and at the same time the supply of bobbins in the magazine is replenished. Upon the delivery of a predetermined number of bobbins to the winding units, switch 177 is closed by the output counter 205 and relay latch coil 195 energized so as to disengage latch device 187 and release armature bar 180 to the action of spring 186 thereby opening switch 185 controlling transport conveyor motor 130. If at this time the predetermined maximum number of empty bobbins has been received in the magazine as determined by input counter 210, switch 178 will have been closed so that latch coil 196 is also energized and the armature bar permitted to move its entire distance sufficient to open switch 184 stopping the supply conveyor. On the other hand, if a sufficient number of bobbins has not been received in the magazine,

switch 178 will remain open so as to render latch device 188 effective to stop armature bar 180 in an intermediate position with switch 184 closed subject to later opening upon closure of switch 178 and disengagement of latch device 188 by 5 latch coil 196. Normally, the rate of delivery of bobbins to the magazine by the supply conveyor is such as to insure an adequate supply of bobbins in the magazine.

Referring now to Fig. 25, the control mechanism there shown is especially designed for use with the magazine 18 of the type shown in Figs. 1 to 12 inclusive. The construction and mode of operation is like that shown in Fig. 24 and above described except for the means for interrupting the supply of empty bobbins to the magazine. The difference resides chiefly in the fact that in this particular embodiment the supply conveyor is stopped in response to the accumulation of a predetermined supply of bobbins in the magazine instead of in response to the passage into the magazine of a predetermined number of bobbins, thereby dispensing with the input counter of Fig. 24 advanced one step for each bobbin delivered to the magazine.

In this instance, the normally open switch 178 controlling energization of the relay latch coil 217 to stop the supply conveyor is controlled by a feeler comprising a plunger 243 (Fig. 12) slidable in the magazine frame and normally urged by a spring 244 out of the path of the bobbins *b* in the magazine. As shown, the inner end of the plunger is equipped with a shoe 245 for engagement with the bobbins. The switch 178 is mounted in a casing 246 carried by a bracket 247 which in turn is mounted upon one of the escapement fingers 73 on the rockshaft 71. The movable contact element 248 of the switch 178 is biased to open position and is arranged for actuation by a spring finger 249 having one end disposed in alignment with the plunger 243. In the oscillation of the rockshaft 71 to carry the supporting escapement finger 73 into the magazine, the finger 249 mounted on the switch casing is moved into engagement with the plunger 243. If no bobbin is disposed in the path of the plunger, the switch 178 will remain open. When, however, the magazine is in filled condition so that the plunger is interrupted in its movement by the presence of a bobbin, the switch will be closed to energize the 50 latch coil 217 of relay 175.

The mode of operation is substantially similar to that of Fig. 24 in that when the transport conveyor has been advanced to deliver a predetermined number of bobbins to the winding units of the winding machine, the switch 177 is closed to cause energization of latch coil 195 with a resulting disengagement of latch device 187 and opening of conveyor motor switch 185. If at this time the magazine contains a predetermined number of bobbins, latch coil 217 will have been energized so as to permit movement of the armature bar 180 through its full distance whereby to effect opening of switch 184 and the interruption of the supply conveyor. In the event, however, that the required number of bobbins has not been delivered to the magazine, latch device 188 will interrupt the armature bar 180 in its intermediate position with the switch 184 closed subject to being opened by the closure of switch 178 when the supply of bobbins in the magazine reaches the established minimum. In this latter respect, the operation is more similar to the mechanical control (Fig. 16) wherein the feeler 153 is periodically actuated and is rendered operative in response to

the presence of a predetermined minimum supply of bobbins in the magazine to disengage the clutch driving the supply conveyor 21.

I claim as my invention:

1. In a bobbin winding machine having a series of uniformly spaced winding units and a cycling mechanism controlling the operation of the machine so as to cause it to operate in successive cycles to wind a group of bobbins simultaneously in each such cycle, means for delivering empty bobbins to the respective winding units including a transport conveyor having a series of receptacles spaced apart according to the spacing of said units and operative to deliver empty bobbins into positions adjacent said winding units, an empty bobbin magazine common to said units for storing a stack of empty bobbins one above the other, escapement means acting in the operation of the transport conveyor to release bobbins from the magazine into said receptacles successively, means operative under the control of said cycling mechanism to effect the advance of the transport conveyor during each winding cycle, means acting to interrupt such advance of the conveyor upon the delivery of a predetermined number of bobbins into positions adjacent the respective winding units, and bobbin replenishing mechanism including a supply conveyor having a drive means and a control means for starting and stopping the same, said control means including a feeler responsive to the accumulation of a predetermined supply of bobbins in the magazine to interrupt the operation of said drive means and to stop the same when a predetermined supply of bobbins has accumulated in the magazine.
2. In a bobbin winding machine having a series of uniformly spaced winding units and a cycling mechanism controlling the operation of the machine so as to cause it to operate in successive cycles to wind a group of bobbins simultaneously in each such cycle, means for delivering empty bobbins to the respective winding units including a transport conveyor having a series of receptacles spaced apart according to the spacing of said units and operative to deliver empty bobbins into positions adjacent said winding units, a magazine common to said units for storing a stack of empty bobbins one above the other, escapement means acting in the operation of the transport conveyor to release bobbins from the magazine into said receptacles successively, means operative under the control of said cycling mechanism to effect the advance of the transport conveyor during each winding cycle, means acting to interrupt such advance of the conveyor upon the delivery of bobbins into positions adjacent the winding units, and a bobbin replenishing mechanism including a supply conveyor having a driving and control means actuated automatically in the advance of the transport conveyor to start the supply conveyor and a feeler responsive to the accumulation of a predetermined supply of bobbins in the magazine and operative to interrupt the advance of the supply conveyor.
3. In a bobbin winding machine having a series of uniformly spaced winding units and a cycling mechanism controlling the operation of the machine so as to cause it to operate in successive cycles to wind a group of bobbins simultaneously in each such cycle, means for delivering empty bobbins to the respective winding units including a transport conveyor having a series of receptacles spaced apart according to the spacing of said units and operative to deliver empty bobbins into positions adjacent said winding units, a

magazine common to said units for storing a stack of empty bobbins, escapement means acting in the operation of the transport conveyor to release bobbins from the magazine into said receptacles successively, drive means for the transport conveyor including a motor and a clutch, means including a latch device operative under the control of said cycling mechanism to effect engagement of the clutch whereby to advance the transport conveyor during each winding cycle, and means driven in timed relation to the transport conveyor and operative after a predetermined advance thereof to actuate said latch device whereby to disengage said clutch.

4. In a bobbin winding machine having a series of uniformly spaced winding units and a cycling mechanism controlling the operation of the machine so as to cause it to operate in successive cycles to wind a group of bobbins simultaneously in each such cycle, means for delivering empty bobbins to the respective winding units including a transport conveyor having a series of receptacles spaced apart according to the spacing of said units and operative to deliver empty bobbins into positions adjacent said winding units, a magazine common to said units for storing a stack of empty bobbins, escapement means acting in the operation of the transport conveyor to release bobbins from the magazine into said receptacles successively, drive means for the transport conveyor including a motor and a clutch, lever means for actuating said clutch spring-biased in a direction to disengage the clutch, means including a latch device operative under the control of said cycling mechanism to actuate said lever means in a direction to engage the clutch and means timed with respect to the operation of the transport conveyor for tripping said latch device to effect disengagement of the clutch by said spring means, said latch device being operative by said cycling mechanism into reengaging relation to said lever means.

5. In a bobbin winding machine having a series of uniformly spaced winding units and a cycling mechanism controlling the operation of the machine so as to cause it to operate in successive cycles to wind a group of bobbins simultaneously in each such cycle, a transport conveyor having a series of receptacles spaced apart according to the spacing of said units and operative to deliver empty bobbins into positions adjacent said winding units, a magazine common to said units for storing a stack of empty bobbins, escapement means acting in the operation of the transport conveyor to release bobbins from the magazines into said receptacles successively, transfer means actuated by said cycling mechanism and operative to transfer empty bobbins in said receptacles to the respective winding units, said transfer means including a rockshaft arranged for actuation by the cycling mechanism, drive means for the conveyor including a clutch, lever means for actuating the clutch, spring means biasing the lever means for movement in a clutch disengaging direction, and means actuated by said rockshaft to actuate said lever means in a clutch engaging direction including a slide operatively associated with the rockshaft, a latch pivoted to the slide and arranged for coaction with said lever means to operate the same, and means operable at a predetermined point in the advance of the conveyor to disengage said latch with respect to said lever means whereby to release the lever means to the action of the spring means to stop the conveyor.

6. In a bobbin winding machine having a series of uniformly spaced winding units and a cycling mechanism controlling the operation of the machine so as to cause it to operate in successive cycles to wind a bobbin simultaneously in each such cycle, means for delivering empty bobbins to the respective winding units including a transport conveyor having a series of bobbin receptacles spaced apart according to the spacing of said units, drive means for said conveyor, a magazine common to said winding units for storing a stack of empty bobbins, means operative in the movement of the transport conveyor by said drive means to release bobbins for the magazine into said receptacles successively, and means for replenishing the supply of bobbins to the magazine including a supply conveyor, drive mechanism for said supply conveyor, and a control device for said conveyor drive mechanism responsive to the accumulation of a predetermined number of bobbins in the magazine to interrupt the operation of the supply conveyor and to a decrease in the number of bobbins in said magazine below said predetermined number to restart the conveyor.

7. In a bobbin winding machine having a series of uniformly spaced winding units and a cycling mechanism controlling the operation of the machine so as to cause it to operate in successive cycles to wind a bobbin simultaneously in each such cycle, means for delivering empty bobbins to the respective winding units including a transport conveyor having a series of bobbin receptacles spaced apart according to the spacing of said units, a magazine common to said winding units for storing a stack of empty bobbins, escapement means operative in the movement of the transport conveyor to release bobbins from the magazine into said receptacles successively, and mechanism for replenishing the supply of bobbins in the magazine including a supply conveyor and a driving and control means therefor operative to start the conveyor as an incident to the operation of the transport conveyor, said control means including a feeler device responsive to the movement of the bobbins relative to the magazine effective to stop the conveyor only in response to the accumulation of a predetermined number of bobbins in the magazine.

8. In a bobbin winding machine having a series of uniformly spaced winding units and a cycling mechanism controlling the operation of the machine so as to cause it to operate in successive cycles to wind a bobbin simultaneously in each such cycle, means for delivering empty bobbins to the respective winding units including a transport conveyor having a series of bobbin receptacles spaced apart according to the spacing of said units, a magazine common to said winding units for storing a stack of empty bobbins, escapement means operative in the movement of the transport conveyor to release bobbins from the magazine into said receptacles successively, and mechanism for replenishing the supply of bobbins in the magazine including a supply conveyor and a driving and control means therefor operative to start the conveyor in timed relation to the winding cycle and to stop the same when a predetermined number of bobbins has accumulated in the magazine, said driving and control means comprising a motor, a clutch spring-biased in a disengaging direction, and means actuated by the transport conveyor to effect engagement of the clutch.

9. In a bobbin winding machine having a series

of uniformly spaced winding units and a cycling mechanism controlling the operation of the machine so as to cause it to operate in successive cycles to wind a bobbin simultaneously in each such cycle, means for delivering empty bobbins to the respective winding units including a transport conveyor having a series of bobbin receptacles spaced apart according to the spacing of said units, a magazine common to said winding units for storing a stack of empty bobbins, means operative in the movement of the transport conveyor to release bobbins from the magazine into said receptacles successively, and mechanism for replenishing the supply of bobbins in the magazine including a supply conveyor and a driving and control means therefor operative to start the conveyor in timed relation to the winding cycle, said driving and control means including a motor having a disengageable clutch connection with the supply conveyor, means actuated in timed relation to the operation of the transport conveyor to render such clutch connection effective to drive the supply conveyor, and means operative when a predetermined number of bobbins has been received in the magazine to render said clutch connection ineffective whereby to stop the supply conveyor.

10. In a bobbin winding machine having a series of uniformly spaced winding units and a cycling mechanism controlling the operation of the machine so as to cause it to operate in successive cycles to wind a bobbin simultaneously in each such cycle, a transport conveyor having a series of bobbin receptacles spaced apart according to the spacing of said units, drive means for said conveyor, a magazine common to said winding units for storing a stack of empty bobbins, means operative in the movement of the transport conveyor by said drive means to release bobbins from the magazine into said receptacles successively, and mechanism for replenishing the supply of bobbins in the magazine including a supply conveyor and a driving and control means therefor comprising a motor, a clutch for connecting the motor to the supply conveyor, spring means tending to disengage said clutch, a feeler responsive to the accumulation of a predetermined number of bobbins in the magazine, and means actuated by the transport conveyor and controlled by said feeler to cause engagement of said clutch when the supply of bobbins in the magazine falls below a predetermined minimum.

11. In a bobbin winding machine having a series of uniformly spaced winding units and a cycling mechanism controlling the operation of the machine so as to cause it to operate in successive cycles to wind a bobbin simultaneously in each such cycle, a transport conveyor having a series of bobbin receptacles spaced apart according to the spacing of said units, drive means for said conveyor, a magazine common to said winding units for storing a stack of empty bobbins, means operative in the movement of the transport conveyor by said drive means to release bobbins from the magazine into said receptacles successively, and mechanism for replenishing the supply of bobbins in the magazine including a supply conveyor, and a driving and control means for the supply conveyor including a motor, a clutch providing a disengageable connection between the motor and the supply conveyor, spring means tending to disengage said clutch, a feeler operatively associated with the upper portion of the magazine and responsive to the accumulation of a predetermined supply of bobbins in the maga-

zine, a rockshaft arranged for actuation by the supply conveyor, a floating lever mounted on said rockshaft and carrying said feeler, and a latch device engageable with said floating lever and operative to hold said clutch engaged against the action of said spring means when the supply of bobbins in the magazine falls below a predetermined minimum.

12. In a bobbin winding machine having a series of uniformly spaced winding units and a cycling mechanism controlling the operation of the machine so as to cause it to operate in successive cycles to wind a bobbin simultaneously in each such cycle, a transport conveyor having a series of bobbin receptacles spaced apart according to the spacing of said units, drive means for said conveyor, a magazine common to said winding units for storing a stack of empty bobbins, escapement means operative in the movement of the transport conveyor by said drive means to release bobbins from the magazine into said receptacles successively, and mechanism for replenishing the supply of bobbins in the magazine including a supply conveyor and a driving and control means therefor including a motor, a clutch providing a disengageable connection between the motor and the supply conveyor, spring means tending to disengage said clutch, a feeler operatively associated with the upper portion of the magazine and responsive to the accumulation of a predetermined supply of bobbins in the magazine, a rockshaft arranged for actuation by the supply conveyor, a floating lever mounted on said rockshaft and carrying said feeler, a latch device engageable with said floating lever and operative to hold said clutch engaged against the action of said spring means when the supply of bobbins in the magazine falls below a predetermined minimum, and means actuated by the transport conveyor for reengaging the latch means with respect to the floating lever.

13. In a bobbin winding machine having a series of winding units spaced apart uniformly in a row and a cycling mechanism controlling the operation of the machine so as to cause said units to operate simultaneously in successive cycles to wind a predetermined number of bobbins, a magazine for empty bobbins, means for delivering empty bobbins to the respective winding units including a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including an electric drive motor for each conveyor, a clutch interposed between each motor and its respective conveyor, means actuated by said cycling mechanism for engaging the transport conveyor clutch to start such conveyor, and means responsive to the release of bobbins from the magazine for engaging the supply conveyor clutch.

14. In a bobbin winding machine having a series of winding units spaced apart uniformly in a row and a cycling mechanism controlling the operation of the machine so as to cause said units to operate simultaneously in successive cycles to wind a predetermined number of bob-

bins, a magazine for empty bobbins, a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including an electric drive motor for each conveyor, a clutch interposed between each motor and its respective conveyor, means actuated by said cycling mechanism for engaging the transport conveyor clutch to start the transport conveyor, means responsive to the release of bobbins from the magazine for engaging the supply conveyor clutch, means operative upon the advance by the transport conveyor of a predetermined number of bobbins to the respective winding units to disengage the clutch for said conveyor, and means operative when a predetermined supply of bobbins is received in said magazine to disengage the clutch for the supply conveyor.

15. In a bobbin winding machine having a series of winding units spaced apart uniformly in a row and a cycling mechanism controlling the operation of the machine so as to cause said units to operate simultaneously in successive cycles to wind a predetermined number of bobbins, a magazine for empty bobbins, means for delivering empty bobbins to the respective winding units including a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including an electric drive motor for each conveyor, a pair of switches respectively controlling the energization of said motors to start said conveyors, electromagnetic means operative upon the initiation of one winding cycle to close said switches, means operative at a predetermined point in the operation of the transport conveyor to open its motor switch, and means operative when a predetermined supply of bobbins is received in said magazine to open the switch to the supply conveyor motor.

16. In a bobbin winding machine having a series of winding units spaced apart uniformly in a row and a cycling mechanism controlling the operation of the machine so as to cause said units to operate simultaneously in successive cycles to wind a predetermined number of bobbins, a magazine for empty bobbins, means for delivering empty bobbins to the respective winding units including a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including an electric drive motor for

each conveyor and electromagnetic means operative upon the initiation of each winding cycle to close said switches and to start said two conveyors, said electromagnetic means being further operative following a predetermined advance of the transport conveyor to interrupt the operation thereof and upon the delivery of a predetermined number of bobbins to the magazine to interrupt the operation of the supply conveyor.

- 10 17. In a bobbin winding machine having a series of winding units spaced apart uniformly in a row and a cycling mechanism controlling the operation of the machine so as to cause said units to operate simultaneously in successive cycles to wind a predetermined number of bobbins, a magazine for empty bobbins, means for delivering empty bobbins to the respective winding units including a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including a relay having a control member, a coil operative upon the initiation of a winding cycle to shift said control member in one direction, a latch for holding said control member in operative position, and a solenoid responsive to a predetermined advance of the transport conveyor for releasing said latch.
- 15 18. In a bobbin winding machine having a series of winding units spaced apart uniformly in a row and a cycling mechanism controlling the operation of the machine so as to cause said units to operate simultaneously in successive cycles to wind a predetermined number of bobbins, a magazine for empty bobbins, means for delivering empty bobbins to the respective winding units including a transport conveyor having a series of bobbin receptacles spaced apart according to the spacing of said units and operable to carry empty bobbins into positions adjacent their respective winding units, means operative in the movement of the transport conveyor to release bobbins from the magazine and deposit them successively in said receptacles, means including a supply conveyor for delivering empty bobbins to said magazine, and a driving and control mechanism for said two conveyors including a relay having a control member spring-biased for movement in one direction, electromagnetic means operative upon the initiation of each winding cycle to shift said control member against the action of said spring, a latch operative to hold said control member in its shifted position, and means operative upon a predetermined advance of the transport conveyor to disengage said latch and release said control member to the action of said spring.
- 20 19. In a bobbin winding machine having a series of laterally spaced winding units, an empty bobbin magazine, a pair of conveyors respectively operative to deliver empty bobbins to the magazine and to transport empty bobbins from the magazine to the respective winding units, and a driving and control mechanism for said two conveyors including a relay comprising a control member having a spring tending to shift it in one direction, electromagnetic means operative in

timed relation to the operation of the winding machine to shift said control member against the action of said spring, a pair of latches engageable with the control member and operative to hold the latter against movement by said spring, solenoids for each of said latches, means operative upon a predetermined advance of the transport conveyor to energize one of said solenoids, and means operative when a predetermined number of bobbins have been received in said magazine to operate the other of said solenoids.

20. In a bobbin winding machine having a series of laterally spaced winding units, an empty bobbin magazine, a pair of conveyors respectively operative to deliver empty bobbins to the magazine and to transport empty bobbins from the magazine to the respective winding units, and a driving and control mechanism for said two conveyors including an electric drive motor for each conveyor, a relay comprising a control member having a spring tending to shift it in one direction, electromagnetic means operative in timed relation to the operation of the winding machine to shift said control member against the action of said spring, a pair of latches engageable with the control member and operative to hold the latter against movement by said spring, solenoids for each of said latches, means operative upon a predetermined advance of the transport conveyor to energize one of said solenoids, and means operative when a predetermined number of bobbins has been received in said magazine to operate the other of said solenoids, each of said conveyor motors having a control switch and said control member having a pair of movable contact elements thereon respectively forming parts of said two switches, one of said contact elements being operable upon release of the control member by one of said solenoids to open the circuit to the transport conveyor motor, and the other contact element being operative upon the energization of the other solenoid to open the circuit to the supply conveyor motor, said two contact elements being differentially spaced with regard to their stationary contacts so as to open the respective switches successively in the movement of the control member by said spring.

21. In a bobbin winding machine having a series of laterally spaced winding units, an empty bobbin magazine, a pair of conveyors respectively operative to deliver empty bobbins to the magazine and to transport empty bobbins from the magazine to the respective winding units, and a driving and control mechanism for said two conveyors including a drive motor for each conveyor, a control member biased for movement in one direction, electromagnetic means for shifting the control means in the opposite direction, a pair of latch devices respectively operative to hold said control member in an extreme position and in an intermediate position, a pair of switches respectively controlling the operation of the two motors and both adapted to be closed when the control member is in its said extreme position and opened successively in the movement of the control member out of its said extreme and intermediate positions, means responsive to a predetermined advance of the transport conveyor to release one of said latches, and means operative when the supply of bobbins in the magazine reaches a predetermined minimum to release the other one of said latches.

22. In a bobbin winding machine having a series of laterally spaced winding units, an empty bobbin magazine, a pair of conveyors respectively

operative to deliver empty bobbins to the magazine and to transport empty bobbins from the magazine to the respective winding units, and a driving and control mechanism including an electric drive motor for each of said conveyors, an input counter responsive to the delivery of a predetermined number of empty bobbins to the magazine, an output counter responsive to the delivery of a predetermined number of bobbins to the winding units, a relay having a pair of switches respectively controlling the operation of said two motors and comprising a control member operable in one direction to close said two switches, and means respectively controlled by said two counters to effect the opening of said two switches.

23. In a bobbin winding machine having a series of laterally spaced winding units, an empty bobbin magazine, a pair of conveyors respectively operative to deliver empty bobbins to the magazine and to transport empty bobbins from the magazine to the respective winding units, and a driving and control mechanism including an electric drive motor for each of said conveyors, an input counter responsive to the delivery of a predetermined number of empty bobbins to the magazine, an output counter responsive to the delivery of a predetermined number of bobbins to the winding units, a relay having a pair of switches respectively controlling the operation of said two motors, a control member operable in one direction to close said two switches, a pair of latch devices respectively operative to hold said control member in either of two positions, and electromagnetic means controlled by the respective counters for operating said latch devices.

24. In a bobbin winding machine having a series of laterally spaced winding units, an empty bobbin magazine, a pair of conveyors respectively operative to deliver empty bobbins to the magazine and to transport empty bobbins from the magazine to the respective winding units, and a driving and control mechanism including a drive motor for each of said conveyors, a pair of switches respectively controlling said two motors, a control member for actuating said switches, said control member being biased for movement in one direction, a pair of latch devices respectively operative to hold said control member in either of two positions, means responsive to a predetermined advance of the transport conveyor for actuating one of said latch devices, and means responsive to the accumulation of a predetermined number of bobbins in the magazine to actuate the other one of said latch devices, said control member being operative when in one position to close both of said switches and when in the other of said two positions to open only one of said switches.

25. In a bobbin winding machine having a series of laterally spaced winding units, an empty bobbin magazine common to said units, a transport conveyor operative to carry empty bobbins from the magazine to the respective units, means operative in the movement of the transport conveyor to release bobbins successively to said conveyor, and means for delivering empty bobbins to the magazine comprising a supply conveyor having an electric drive motor, a switch controlling energization of said motor, and means for opening said switch to interrupt the supply of bobbins to the magazine including a feeler responsive to the delivery of bobbins to the magazine, an input counter, and electromagnetic

means controlled by said feeler for actuating said counter.

26. In a machine for winding filling wound bobbins comprising a series of laterally spaced winding units, a magazine common to said units and providing a vertical guideway for receiving the butt ends of the bobbins with the stem ends thereof projecting laterally from the guideway, a transport conveyor operatively associated with the lower end of the magazine and operative to carry empty bobbins from the magazine to said units, an escapement mechanism controlling the successive release of bobbins from the magazine to the conveyor, a slideway supporting bobbins for movement into the upper end of the guideway with the bobbins in upright position, a rockshaft at one side of the magazine and a plurality of escapement fingers spaced apart vertically along the rockshaft and movable into and out of the path of movement of the bobbins along the guideway whereby to control the descent of bobbins in the guideway with the bobbins in substantially horizontal position, and a clamping member operative in the rocking of said shaft to periodically

engage with the butt ends of the bobbins to maintain them in horizontal position during the movement of the escapement fingers into positions between the bobbins.
